DESIGN FOR A TOP GRATE FOR A STOVE OR ANALOGOUS ARTICLE

Charles Stanchfield, Milwaukee, Wis., assignor to
A. J. Lindemann & Hoverson Company, Milwaukee,
Wis., a corporation of Wisconsin

Application February 17, 1940, Serial No. 90,337

Term of patent 7 years

To all whom it may concern:

Be it known that I, Charles Stanchfield, a citizen of the United States, residing in the city of Milwaukee, county of Milwaukee, and State of Wisconsin, have invented a new, original, and ornamental Design for a Top Grate for a Stove or Analagous Article, of which the following is a specification, reference being had to the accompanying drawing, forming a part thereof.

The figure is a perspective view of a top grate for a stove or analagous article showing my design.

The other side of the article is substantially like the side shown.

I claim:

The ornamental design for a top grate for a stove or analagous article, as shown and described.

CHARLES STANCHFIELD.
